Primary Examiner — Kendra Leslie Hamilton*Assistant Examiner* — Elizabeth S Struble(74) *Attorney, Agent, or Firm* — Christopher A. Rothe; Culhane Meadows PLLC(57) **CLAIM**

The ornamental design for a syringe pump, as shown and described.

DESCRIPTION

FIG. 1 is a perspective view of a syringe pump with a lid in a closed position;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is another perspective view of the syringe pump with the lid in an open position; and,

FIG. 8 is a front view thereof.

In the drawings, the equal-length broken lines depict portions of the syringe pump that form no part of the claimed design.

1 Claim, 6 Drawing Sheets(56)
